CURTAIN ROD GUIDE

Marie E. Prouse, Los Angeles, Calif.

Application November 1, 1948, Serial No. 149,428

Term of patent 14 years

(Cl. D21—6)

To all whom it may concern:

Be it known that I, Marie E. Prouse, a citizen of the United States, residing at Los Angeles, in the county of Los Angeles and State of California, have invented a new, original, and ornamental Design for Curtain Rod Guide, of which the following is a specification, reference being had to the accompanying drawing, forming a part thereof.

Figure 1 is a perspective view of a curtain rod guide, showing my new design.

Figure 2 is an end elevation of Figure 1, as viewed from the left.

Figure 3 is an end elevation of Figure 1, as viewed from the right.

Figure 4 is a top plan view of the curtain rod guide.

I claim:

The ornamental design for a curtain rod guide, substantially as shown.

MARIE E. PROUSE.
